Inc. J. Rathbone of Albany N. Y.
Letters Patent No. 291. Dated June 18. 1850.

The Schedule referred to in these Letters Patent and making part of the same.

To whom it may concern:

Be it known that I, John J. Rathbone of the City of Albany & State of New York, have produced a new & original Ornamental Design for a Parlour Stove, and I do hereby declare that the annexed and accompanying drawings are a full & accurate delineation of the ornamented parts, with their several ornaments, the back plate which is not represented being precisely similar to the front plate, represented, and the end plate, which is not represented being precisely similar to the end plate represented, and where portions of plates are shewn, the portions not shewn being symmetrical with them and similarly ornamented.

What I claim as my production and desire to secure by Letters Patent is the combination and arrangement of Ornamental figures and forms represented in the accompanying drawings, forming together an Ornamental Design for a Parlour Stove.

Witnesses.
